UNITED STATES PATENT OFFICE.

DANIEL P. FARRELL, OF DAYTON, OHIO.

CARPET-BEATER.

SPECIFICATION forming part of Letters Patent No. 789,598, dated May 9, 1905.

Application filed April 11, 1903. Serial No. 152,216.

To all whom it may concern:

Be it known that I, DANIEL P. FARRELL, a citizen of the United States, residing at Dayton, in the county of Montgomery and State 5 of Ohio, have invented new and useful Improvements in Carpet-Beaters, of which the following is a specification.

My invention has relation to new and useful improvements in carpet-beating machines 10 of that character or type embodying in their structure mechanically-operated cleaning devices arranged and constructed to engage and operate upon the surface of a moving web of fabric for the purpose of removing loose particles of dirt therefrom.

The primary object of the invention is to provide an improved machine of the character mentioned which will efficiently accomplish the purposes for which it is constructed.

20 A further object is to provide an improved means for carrying the carpet, which is so constructed that the carpet may be moved into and out of position to be operated upon by the beaters and which will be readily adjustable for the purpose of carrying webs of carpets of different lengths and for regulating the tension on said web.

25 A further object is to provide a plurality of beaters and an improved means associated therewith whereby they may be thrown independently into and out of operative relation with their operating means.

The invention consists in the improved construction and arrangement of the various elements in operative combination, the novelty 35 of which will be fully described hereinafter and particularly pointed out and distinctly claimed.

I have fully and clearly illustrated my invention in the accompanying drawings, forming 40 a part of this specification, and wherein—

Figure 1 is a view in front elevation of a carpet-beating machine constructed in accordance with my invention. Fig. 2 is a view in 45 rear elevation of the carpet-beating machine. Fig. 3 is a side elevation. Fig. 4 is a view in elevation of the opposite side of the machine from that shown in Fig. 3. Fig. 5 is a top plan view of the machine. Fig. 6 is a section 50 through a portion of the horizontal bar in

which the guide-blocks for the beater-operating rods are arranged, and Fig. 7 is a detail view of a modified form of reel.

Referring to the drawings, the machine embodying my invention is shown as supported 55 for operation upon a suitable base-frame or foundation constructed of longitudinal and transverse timbers 1 2, suitably united and braced in order to provide a firm and rigid base for the machine. On the transverse timbers 2 are provided suitable bearings, in which is journaled a transverse horizontally-arranged shaft 3, upon which are rigidly mounted belt-pulleys 4, 5, and 6, substantially as shown in Fig. 5.

60 Arranged upon the base-frame of the machine at a distance from each other are vertical standards or posts 7 8, on which are respectively secured bearings 9 10. Within these bearings is rotatably mounted a horizontal shaft 11, which runs parallel with the shaft 3 and upon which are loosely mounted a plurality of sleeves or hubs 12, which are loosely arranged in order that the shaft may have movement independent of said hubs. 65

Each of these hubs is provided with diametrically-arranged radial trip arms or fingers 13 14, which are adapted when the hubs are positively connected to the shaft and are rotated thereby to engage the beaters to operate them 70 to beat the carpet, as will be described hereinafter. The hubs 12 just mentioned are spaced apart suitable distances on the shaft 11 and are rigidly connected thereto when it is desired to operate the beater by means of 75

clutches 15, which are slidably arranged on said shaft and are provided with proper faces adapted to engage coacting clutch-faces formed on the sides of the hubs 12, substantially as shown in Figs. 1, 2, and 5 of the drawings. 80 These clutches 15 are connected to the shaft to always rotate therewith by means of longitudinal ribs 16 on said shaft, which are arranged to engage grooves formed on the interior of said clutches. In order to operate 85 the clutches to be thrown into and out of engagement with the hubs 12, I provide clutch-levers 17, which are fulcrumed on brackets 18, mounted on the standards 7 and 8, which 90 carry the shaft 11.

Secured at a suitable point above the shaft 11 and the tripping devices carried thereby is arranged a horizontal bar 19, which is rigidly supported upon the standards 7 and 8. This 5 bar 19 is formed on its top side at distances corresponding to the distance at which the tripping devices are spaced with a plurality of recesses 20, in the end walls of which are formed alining seats or bearings 21, in which 10 are journaled trunnions 22, formed integral with the guide-blocks 23, arranged in the said recesses and which have a rocking movement on their trunnions. These trunnions are held seated in the bearings 21 by means of bearing-blocks 24, seated in said recesses and the 15 ends of which set over the trunnions, said blocks being held rigidly in position by bolts, as shown in Fig. 6.

Extending entirely through the rocking 20 guide-blocks 23 from side to side are transversely-arranged openings 25, within which are disposed longitudinally-sliding rods 26, the front ends of which are securely fastened to the beaters 27, which comprise vertically-extending 25 spring members fastened at their lower ends to the base-frame and carrying at their upper free ends transversely-arranged beating-heads 28, which, as shown, are arranged in lapped relation in order that the 30 material being cleaned will be repeatedly struck at the same point when the machine is in operation.

Upon the rear ends of the sliding rods 26 are sleeved depending fingers 29, which are 35 slidably adjustable along said rods and are secured in adjusted position by means of set-screws 30, passing through said fingers and engaging the rods. This adjustment of the 40 fingers 29 provides an efficient means for regulating the force of the blow given by the beaters, since it will be seen that the closer the fingers are moved toward the beaters the farther the rods 26 will be drawn rearwardly by the fingers 13 14 and that the farther the 45 rods are moved the greater will be the force of the blow.

It will be perceived that when the shaft 11 is rotated the oppositely-disposed trip-fingers 13 and 14, carried by the hubs 12 on said 50 shaft, will intermittently engage the fingers 29 on the rods 26, which will slide said rods rearwardly, drawing back the beaters against the force of the springs 27, and that as soon as the continued revolution of the shaft carries the fingers 13 and 14 out of engagement 55 with the fingers 29 the spring members 27 will throw the beating-heads into contact with the carpet.

The shaft 11, just mentioned, is driven by 60 a power-belt 11^a, which is arranged on the pulley 4, mounted on the shaft 3, which belt also passes over a pulley 31, arranged on said shaft 11, whereby rotary movement of the shaft 3 imparts a similar movement to the 65 shaft 11. On the shaft 11 is also provided an

idle pulley 32, adjacent the pulley 31 and onto which the belt may be shifted when it is desired to throw the beaters out of operation without stopping the entire machine.

In combination with the beaters I employ 70 a carpet-carrying means of novel construction which is arranged to be swung toward and away from the beaters in order that the carpet on said carrying means may be brought into and moved out of position to be acted 75 upon by the beaters. This carrying means embraces in its structure two vertically-arranged shafts 33 34, which for a distance from their upper ends downwardly are threaded, as at 35 36, respectively, and on these 80 threaded portions are arranged vertically-movable internally-threaded blocks 37 38, the threads of said blocks operatively engaging the threads on the shafts. The shafts 33 and 34 are provided at points below their threaded portions with annular recesses 38^a and 38^b, respectively, adapted to receive tongues 38^c of sleeves 38^d and 38^e to secure said sleeves in applied position upon the shafts in order 85 that the sleeves may be held against rotation without interfering with the rotation of the shafts 33 and 34. The sleeves are held against rotation by means of a transverse bar 53, the ends of which are rigidly secured to said sleeves, and it also serves to add rigidity and 90 strength to the structure. On each of said sleeves at a point below the threaded portions of the shafts are provided blocks 39 40, similar 95 in structure to the blocks 37 38, said blocks 39 and 40 being rigidly fixed to the sleeves 100 against vertical movement in order that the rotation of said shafts will move the blocks 37 38 toward and away from the blocks 39 40. The blocks from the point at which they engage 105 the shafts project laterally in opposite directions to provide horizontally-arranged arms, the opposite ends of which are provided with bearings, those in the upper arm being designated by 41 and 42, in which are journaled the opposite ends of shafts or rollers 110 43 44, while the lower blocks are provided with bearings 45 46, in which are journaled rollers 47 48, the rollers carried by the respective blocks being so disposed that when 115 the carpet is placed thereon in the form of an endless belt it can be retained in frictional contact with the rollers by rotating the shafts 33 and 34, which will serve by virtue of the threaded connection thereof with the blocks 37 38 to adjust said blocks vertically and 120 move the rollers carried thereby toward or away from those journaled in the blocks 39 40 to accommodate the length of the carpet.

49 designates a vertical standard supported upon the base-frame and formed at its upper 125 terminal with a horizontal laterally-extending arm 50, in the free end of which is a bearing 51, in which is journaled the upper end of the shaft 34, the lower end of which being journaled in a step-bearing 52, so that said 130

shaft will be held against lateral movement, but be free to rotate. The lower end of the shaft 33 is journaled in a carriage 75^a, which is provided with a caster 76, adapted to travel 5 on a curved track 77, so that by using the shaft 34 as a pivot the entire carpet-carrying means may be swung away from or toward the beaters.

On the lower end of the vertical shaft 34 is 10 a bevel-gear 54, which meshes with a bevel-gear 55, mounted on a horizontal shaft 56, journaled in suitable bearings on the base-frame, and which shaft is driven by a belt (not shown) passing over a pulley 57, rigidly 15 mounted on the shaft 56 and interposed between the idle pulleys 58 59, also mounted on said shaft. An endless power-belt 60 leads from the pulley 6 to the pulley 59, and a twisted belt 61 leads from said pulley 6 to the 20 idle pulley 58. A belt-shifter of any approved construction (not shown) may be employed to shift either of the belts 60 61 onto the pulley 57, according to the direction in which it is desired to rotate the shaft 56. By 25 rotating the shaft 56 in one direction the bevel-gear 54 on the shaft 34 will be rotated to turn said shaft and will also rotate the bevel-gear 62 on the shaft 63, one end of which is journaled in a bearing 64, secured to the 30 lower end of the sleeve 38^e, and its other end is journaled in a bearing 65, carried by the carriage 75^a. As the shaft 63 rotates the bevel-gear 66 thereon will also turn, and as 35 this gear meshes with the bevel-gear 67 on the shaft 33 said shaft will be rotated at the same speed and simultaneously with the shaft 34, thus causing the upper blocks 37 38 to be moved toward or away from the blocks 39 40, which are fixedly mounted on the sleeves. 40 The shaft 48 extends through the block 40 and is provided at one end with an extension 68, on the extremity of which is located a clutch-face 69, which is adapted to be engaged by the face 70 of a clutch 71, slidably 45 arranged on a shaft 72, which is journaled in bearings formed in the vertical standard 49, said clutch being operated by a lever 70^a, fulcrumed on a bracket 71^a on said standard. At a point intermediate its ends the standard 50 49 is provided with a slot 73, through which the shaft 72 extends and within which is arranged a pulley 74, carried by said shaft 72. This pulley 74 and the shaft 72 are driven by means of a belt 75, which passes over the pulley 74 and over the pulley 5 on the line-shaft 3, as shown in Figs. 3 and 5 of the drawings.

I also provide a track 78, oppositely disposed to the arc of the rack 77, so that a carpet-carrying means may be pivoted to the opposite side of the beaters from that just mentioned, so that one of said means may be placed in the path of the beaters while the material to be cleaned is being placed on the opposite means.

65 By reference to Fig. 5 of the drawings it

will be seen that the clutch-face 69, carried by the extension 68 on the shaft 48, is out of engagement with the face 70 of the clutch 71 on the shaft 72 when the carpet-carrying means is swung to move the carpet out of operative position to be acted upon by the beaters, so that the said shaft 48 will cease to rotate. As soon, however, as the carpet-carrying means is swung back to bring the carpet in position to be cleaned the clutch-face 69 on the shaft 48 will be brought into position to be engaged by the clutch 71 in order that the shaft 48 may be rotated to move the carpet. This movement of the carpet enables the same to pass before the beaters at a suitable speed, so that all points of the carpet are struck by the beaters. It will be observed that by operating the clutches on the shaft 11 any one of the tripping devices may be thrown out of operative engagement with relation to 85 the beaters.

In Fig. 7 of the drawings I have shown a modified form of the carpet-carrying means in which is employed two blocks 79 on each shaft 33 and 34 and which are provided with 90 suitable bearings in which are journaled two large drums or rollers 80 81 instead of the rollers 43, 44, 47, and 48 shown in the preferred form of the invention.

It will be seen that as the rods 26 are moved 95 rearwardly by means of the tripping devices the guide-blocks 23, through which the rods reciprocate, will rock on their trunnions in order to provide for a free and easy movement of the rods and prevent undue bending 100 or torsional strain, to which they would be subjected were the guides fixed and immovable.

What I claim, and desire to secure by Letters Patent, is—

1. In a carpet-cleaning machine, a cleaning mechanism, and a carpet-carrying means movable toward and from the cleaning mechanism, said carpet-carrying means comprising shafts, other blocks adjustably mounted on the shafts, other blocks rigidly supported in alinement with said first-named blocks, rollers mounted on said blocks, and means for adjusting the blocks.

2. In a carpet-cleaning machine, a plurality of beaters, pivoted blocks, a rod connected to each beater and engaging the blocks, operating devices for the beaters, and means for throwing each of said operating devices into and out of operative position.

3. In a carpet-cleaning machine, the combination with a carpet-cleaning mechanism and a carpet-carrying means, said means comprising vertical shafts, upper blocks carried by the shafts, lower blocks rigidly supported in alinement with said upper blocks, rollers carried by the blocks, and means to adjust the upper blocks with relation to the lower blocks.

4. In a carpet-cleaning machine, the combination with a carpet-cleaning mechanism and a carpet-carrying means, said means compris-

- ing two vertical shafts, one of which is journaled in fixed bearings, and the other of which is connected to the fixed shaft and adapted to swing in a circle with the fixed shaft as a pivot, blocks carried by the respective shafts, other blocks supported in alinement with the first-named blocks, and rollers carried by the blocks.
5. In a carpet-cleaning machine, the combination of a plurality of beaters, pivoted guide-blocks, a rod connected to each beater and projecting through the guide-blocks, and means for intermittently engaging the rods to actuate the beaters.
- 10 6. In a carpet-cleaning machine, the combination of a plurality of beaters, rocking blocks having guides, a rod connected to each beater and engaging said guides, a finger on the end of each rod and means for intermittently engaging the fingers to actuate the beaters.
- 15 7. In a carpet-cleaning machine, the combination with a cleaning mechanism, of a carpet-carrying means, said means comprising vertical threaded shafts, blocks threaded on the shafts, other blocks rigidly mounted in vertical alinement with said first-named blocks, rollers journaled in the blocks, and means to rotate the shafts to adjust the first-named blocks with relation to the rigid blocks.
- 20 8. In a carpet-cleaning machine, the combination with a cleaning mechanism, of a movable carpet-carrying means comprising vertical shafts, blocks on said shafts, other blocks rigidly mounted in vertical alinement with the first-named blocks, rollers journaled in the blocks, means to drive the rollers when the carpet is being cleaned, said rollers being disconnected from the driving means when the carrying means is moved out of operative position.
- 25 9. In a carpet-cleaning machine, a plurality of beaters, pivoted blocks, a rod connected to each beater and engaging the blocks, fingers carried by the rods, a shaft, hubs mounted upon said shaft, fingers carried by the hubs and adapted to engage the first-named fingers to actuate the beaters, and means for throwing one or more of said hubs into or out of operation.
- 30 10. In a carpet-cleaning machine, a plurality of beaters, pivoted guide-blocks, rods connected to the beaters and engaging the blocks, means for engaging the rods to actuate the beaters, and a carpet-carrying means movable toward and away from the beaters.
- 35 11. In a carpet-cleaning machine, a frame, posts secured to said frame, a bar secured to said posts and provided with recesses, guide-blocks pivotally mounted in said recesses, bearing-blocks adapted to secure said guide-blocks in applied position, spring members, each having one of its ends secured to the frame, beating-heads carried by the free ends of said spring members, rods connected to the 40 spring members and engaging the guide-blocks, and means for engaging the rods to actuate the beaters.
- 45 12. In a carpet-cleaning machine, the combination of a plurality of beaters, a shaft, operating devices for the beaters loosely mounted on the shaft, and means for independently placing said devices in operative relation to the shaft.
- 50 13. In a carpet-cleaning machine, a frame, posts secured to said frame, a bar secured to said posts and provided with recesses, guide-blocks pivotally mounted in said recesses, bearing-blocks adapted to secure said guide-blocks in applied position, spring members, each having one of its ends secured to the frame, beating-heads carried by the free ends of said spring members, rods connected to the spring members and engaging the guide-blocks, a shaft journaled upon said posts, means for rotating the shaft, hubs loosely mounted upon the shaft, fingers carried by the hubs to engage the rods to actuate the beating-heads, and means for throwing each of said hubs into and out of operation.
- 55 14. In a carpet-cleaning machine, a frame, a cleaning mechanism mounted on the frame, a standard mounted upon the frame and having its upper end provided with a bearing, a bearing arranged adjacent to the frame and in alinement with the first-named bearing, a shaft having a portion thereof screw-threaded and journaled in said bearings, another shaft having a portion thereof screw-threaded, means for connecting said shafts to permit the last-named shaft to be swung and the first-named shaft to act as a pivot, blocks mounted on the threaded portions of the shafts, other blocks rigidly mounted in vertical alinement with the first-named blocks, rollers carried by said blocks, means for rotating said shafts to cause the first-named blocks to move toward and from the last-named blocks, a shaft carried by the frame, a clutch member carried by one of said rollers, another clutch member carried by said shaft and adapted to be thrown into and out of engagement with the clutch member carried by one of said rollers, and means for imparting rotation to the last-named shaft.
- 60 15. In a carpet-cleaning machine, a cleaning mechanism, and a carpet-carrying means, said means comprising shafts, one of which is journaled in a fixed bearing and the other in a movable bearing, blocks movably mounted on the shafts, other blocks rigidly supported in alinement with the first-named blocks, rollers journaled in the blocks, a shaft, a clutch member carried by one of the rollers, another clutch member carried by the second-named shaft and adapted to be thrown into and out of engagement with said first-named clutch member, gears secured to the first-named shafts, a drive-shaft, a gear secured thereto and meshing with one of the gears of the first-named shafts, another shaft, and gears secured to the last-named shaft and meshing

with the gears carried by the first-named shafts.

16. In a carpet-cleaning machine, a cleaning mechanism, and a carpet-carrying means, said means comprising shafts, one of which is journaled in a fixed bearing and the other in a movable bearing, means for connecting the shafts, blocks movably mounted on said shafts, other blocks rigidly supported in alinement with the first-named blocks, rollers journaled in the blocks, means for rotating the rollers, gears secured to the lower ends of the shafts, a drive-shaft, a gear secured thereto and meshing with one of the gears on the shafts, another shaft, and gears thereon and meshing ¹⁵ with the gears on the first-named shafts.

In testimony whereof I affix my signature in presence of two witnesses.

DANIEL P. FARRELL.
